(74) Attorney, Agent, or Firm — WHDA, LLP

CLAIM

The ornamental design for an all-terrain vehicle and/or replica thereof, as shown and described.

DESCRIPTION

FIG. 1 is a front right side perspective view of an all-terrain vehicle and/or replica thereof, showing my new design; FIG. 2 is a front left side perspective view thereof; FIG. 3 is a rear right side perspective view thereof; FIG. 4 is a rear left side perspective view thereof; FIG. 5 is a front elevational view thereof; FIG. 6 is a rear elevational view thereof; FIG. 7 is a right side elevational view thereof; FIG. 8 is a left side elevational view thereof; FIG. 9 is a top plan view thereof; and, FIG. 10 is a bottom plan view thereof. The claimed design is indicated by the relatively dark portions in the figures, while the de-emphasized grayscale portions form no part of the claimed design.

1 Claim, 10 Drawing Sheets
